UNITED STATES PATENT OFFICE.

THOMAS GRAHAM, OF CHICAGO, ILLINOIS.

REFLECTOSCOPE.

1,086,704.

Specification of Letters Patent.

Patented Feb. 10, 1914.

Application filed April 3, 1909, Serial No. 487,637. Renewed December 15, 1913. Serial No. 806,910.

To all whom it may concern:

Be it known that I, THOMAS GRAHAM, a citizen of the United States, residing at Chicago, county of Cook, State of Illinois, have 5 invented a certain new and useful Improvement in Reflectoscopes, and declare the following to be a full, clear, and exact description of the same, such as will enable others skilled in the art to which it pertains to 10 make and use the same, reference being had to the accompanying drawings, which form a part of this specification.

My invention relates to apparatuses for throwing upon a screen or the like enlarged 15 reflections of pictures or the like and it has for its object to simplify and improve the construction and manner of using the same.

A further object of my invention is to produce an apparatus of the character 20 specified which may be illuminated from any source of illumination usually found in dwellings.

A further object of my invention is to make it possible for an apparatus of the 25 character specified to be illuminated by means of an ordinary reading lamp which, at other times, may serve as a reading lamp without being changed in any way.

The various features of novelty whereby 30 my invention is characterized will hereinafter be pointed out with particularity in the claims; but, for a full understanding of my invention and of its objects and advantages, reference may be had to the following detailed description taken in connection with the accompanying drawings, wherein:

Figure 1 is a front elevation of my improved apparatus, a portion being in section, showing the manner of using it with an ordinary reading lamp; Fig. 2 is a plan view of the apparatus; Fig. 3 is a section taken on line 3-3 of Fig. 1; Fig. 4 is an edge view of an improved card-holder; 45 Fig. 5 is a view of the lamp shown in Fig. 1 employed as a reading lamp; and Fig. 6 is a section taken through the apparatus showing the manner of using it with a gas burner or with an electric light.

50 Referring to the drawings, A represents a reflectoscope casing having at the front thereof a lens-supporting tube B. The lenses are not shown since their construction

and arrangement is well known. The rear wall of the casing is in the form of a door 55 C hinged as at c at its lower edge. In one corner of the lower wall is an opening preferably formed by providing a short tubular projection D, open at the top, at this point. Directly above the opening in the bottom 60 is a second opening E in the top wall of the casing. The opening E is preferably surrounded by a short annular flange F projecting upwardly from the casing.

G is a chimney member which is preferably detachably secured in place by fitting closely around the flange F. Upon the top of the chimney is a perforated cover H which is preferably detachable.

I is a hood which overlies the cover at 70 some distance above it; the hood being detachably held in place in any suitable manner as, for example, by means of spring clips i. At the two sides of the casing are secured upright tubes K and K¹. In the 75 corner of the casing adjacent to the member D and the chimney is a reflector L situated so as to concentrate the light from a source in front of it upon the door at the rear of the casing.

Secured upon the inner surface of the hinged door is a card-holder M consisting preferably of a flat plate having two of its edges turned in as at m. The card-holder is preferably bowed as shown so as to carry 85 its ends nearer the front of the casing than the middle thereof. A card which is to be shown is slipped upon the holder with its edges underlying the inturned portions m which act both as guides and means for 90 holding the card in place. The holder is preferably secured in position so that it may readily be detached or turned at an angle of ninety degrees from the position shown in Fig. 3.

95 By making the holder revoluble it is possible to reproduce pictures upon the screen in upright positions regardless of whether they are arranged lengthwise or crosswise of a card. It is often desirable to show a 100 series of pictures one after the other where they are all mounted on a single strip. Thus, for example, it may be desired to reflect a series of pictures cut from the comic section of a Sunday newspaper. In such 105 case the card-holder may be entirely re-

moved by simply unscrewing the thumb-nut N. The strip is then placed between the door and the adjacent edges of the casing and is moved step by step until all of the pictures have been reflected.

In Fig. 1 I have shown the reflectoscope associated with an ordinary reading lamp so as to be illuminated thereby. O represents a lamp. o a seat for receiving the ring p of a shade-supporting tripod P when the lamp is used as a reading lamp as shown in Fig. 5. When the lamp is to be used with a reflectoscope the shade O¹, the chimney O², and the tripod are removed and the burner 15 of the lamp is then inserted through the tube D until the lower edge of the tube engages with the seat o. A closure is thus provided for the opening in the bottom of the casing and at the same time the casing is wholly 20 or partially supported on the lamp. The combustion gases can escape through the chimney but the hood above the chimney prevents the rays of light from passing upwardly. The burner O³ of the lamp lies in 25 front of the reflector so that its rays are concentrated and reflected against the door at the rear of the casing. O⁵ is a lamp chimney extending into the chimney G.

Since the casing rests upon the lamp at 30 one corner thereof, I prefer to provide additional supporting means therefor. To this end I employ a base plate Q upon which the lamp may rest, the base plate having an upwardly-projecting tubular member q which 35 will register with the tube K secured to the casing. A rod Q¹ is inserted through the tube K and into the tube q. The upper end of the tube q serves to support the casing and the rod prevents lateral displacement of 40 the casing upon this tube.

In Fig. 6 I have shown the manner of illuminating the reflectoscope by means of gas or electricity. R is a base plate having thereon a pair of vertically-extending tubes 45 r and r¹ which are spaced apart the same distance as the tubes K and K¹. R¹ is a gas burner mounted upon the base. The parts are so constructed and arranged that when the tube D of the casing is slipped 50 down over the burner, the casing will be supported upon the upper ends of the tubes r and r¹ and the casing may be locked in position by means of rods k and k¹ inserted through the tubes K and K¹ and projecting 55 into the tubes r and r¹. By providing the burner with a mantle such as shown in dotted lines in Fig. 1, the illumination will be at the proper point relative to the reflector. Furthermore, a lamp chimney similar to the 60 chimney O⁵ should be employed.

When it is desired to illuminate the reflectoscope by means of an electric light, the base R or one similar thereto is employed; the hood I is removed and an electric socket 65 S is placed in the cover H. The cover H

is provided with a central opening h of a size sufficient to receive and hold the socket.

The cover may be detached and a bulb T screwed into the socket and the cover again replaced, holding the bulb in front of the reflector. When the gas or a reading lamp is to be used, the chimney cover or the entire chimney is detached, the bulb is unscrewed and removed and then the socket is withdrawn; the chimney cover or the chimney is 75 then replaced and the hood is added.

It will be seen that the cover H is provided with a number of perforations, h¹, in addition to the central opening h. These perforations afford ventilation when the casing is being illuminated electrically, the hot air escaping, and the card or other device being displayed being protected against undue heat. Where the illumination is by means of the lamp or the gas, the combustion gases are conveyed upwardly by means of the lamp chimneys into the main chimney; so that the interior of the casing remains comparatively cool regardless of the source of illumination, and the cards are prevented 85 from being injured.

A further protection for the cards is afforded by the expedient of hinging the door at the rear of the casing and making no provision for locking the door in place. It 95 is thus impossible for the operator to go away and leave a card exposed to the heat of the illuminating device for, as soon as the operator releases the door, it drops down carrying the card with it.

In apparatuses of this kind the reflectors tarnish very readily and often destroy the value of the apparatuses when they are otherwise as good as new. In order to minimize the evil due to tarnishing of the reflectors, I make them detachable so that they may be taken out and cleaned or even be replaced by new ones should they become damaged. To this end the reflector may take the form of a sheet of resilient material, such 105 as German silver, and be sprung in place in the casing. In the arrangement shown, the reflector L is sprung into position between a lug a on the casing and the portion b of the tube B which projects into the casing. The 115 reflector is held in place through its own resiliency and can easily be removed and replaced.

I prefer to make the interior of the casing a dead black so that there will be no interference of light due to reflection from the walls.

It will now be seen that I have provided a simple and novel arrangement whereby a reflectoscope may be illuminated from 125 any usual source of light, an oil or alcohol lamp being provided which may be used for illumination as a reading lamp or a lamp for any usual purpose when not otherwise employed.

Having now fully described my invention, what I claim as new and desire to secure by Letters Patent is:

1. In combination, a lamp having a seat 5 for a shade-holder, a reflectoscope having an opening therein at one side of a size to permit the reflectoscope to rest upon said seat with the chimney of the lamp extending into the reflectoscope, and a supporting device 10 arranged at the opposite side of the reflectoscope to coöperate with said seat for supporting the weight of the reflectoscope.
  2. In a reflectoscope, a casing, a door hinged to said casing, a source of light within 15 the casing, and a revoluble card holder mounted on said door in position to receive rays of light from said source.
  3. In a reflectoscope, a casing, a lens-supporting tube on said casing, a door hinged 20 to the casing in rear of said tube, and a card holder revolubly mounted on the interior of said door and curved forwardly at the ends toward said tube.
  4. In a reflectoscope, a casing having an 25 opening therein for the passage of a burner, a reflector in said casing, a chimney above said opening, a cover detachably mounted on said chimney, said covering having an opening therein of a size to fit an electric 30 light socket, the length of the chimney being such that a bulb secured within a socket held by said cover extends into said casing in front of said reflector, a lamp having a seat thereon, a supporting device arranged 35 to support said casing in a position wherein the casing rests upon said seat on the lamp with the chimney extending through said opening, the arrangement being such that a part of the weight of the casing is supported by the lamp and the remainder by 40 the said supporting device.
  5. In combination, a lamp having a seat surrounding the burner, a base plate for supporting said lamp, a vertical tube on said 45 base plate, a reflectoscope arranged to rest on said seat, a vertical tube on said reflectoscope in position to aline with the tube on the base plate, and a rod extending loosely into said tubes, said tubes being so proportioned that one rests upon the other when the reflectoscope rests upon said seat.
  6. In combination, a casing, shoulders in the casing, a card support in the casing, a source of illumination, and a reflector comprising 50 a sheet of resilient metal sprung in position between said shoulders.
  7. In a reflectoscope, a casing, a lens-supporting tube on said casing, a card-holder mounted in rear of said tube, a source of 55 light in the casing, a shoullder in the casing, 60 and a reflector comprising a sheet of resilient metal sprung in position between said tube and said shoulder.
  8. In a reflectoscope, a casing, a lens-supporting tube on said casing, a door movably 65 mounted on the casing in rear of said tube, a source of light within the casing, and a revoluble card holder mounted on said door in position to receive rays of light from said source. 70
  9. In a reflectoscope, a casing, a lens-supporting tube on said casing, a door movably mounted on the casing in rear of said tube and a card holder revolubly mounted on the interior of said door and curved forwardly 75 at its ends toward said tube.
  10. An opaque picture holder provided with means for holding a picture thereon by its edges, pivotally mounted on a support so that it can rotate thereon about the optical axis of the objective lens, substantially 80 as specified.
  11. An opaque picture holder for use in apparatus of the class described, consisting of a curved or bent picture-supporting back, 85 having its two opposing curved edges fitted with grooves to receive the edges of the picture, substantially as specified.
  12. A picture holder for an opaque picture projecting apparatus consisting of an 90 integral piece of plate having two opposite edges folded over to form a flanged groove at each edge to receive and retain the edges of the picture, and bent or curved in concave form on its flanged side, said plate being 95 pivotally attached to a support so as to rotate about the optical axis of the lens, substantially as specified.
  13. In an instrument for the purposes specified, a picture holder provided with a 100 pair of curved picture-edge-retaining grooves which are continuous or unbroken throughout substantially their entire length, substantially as specified.
  14. In an instrument of the class described, a picture holder provided with a pair of picture-edge-retaining grooves which are curved in relation to the objective lens and are continuous or unbroken throughout substantially their entire length, substantially as specified. 105
- In testimony whereof, I sign this specification in the presence of two witnesses.
